THEATER CHAIR

Grover Cleveland Jones, Bronx, N. Y., assignor
of one-half to Morris B. Geris, Bronx, N. Y.

Application March 24, 1948, Serial No. 16,735

5 Claims. (Cl. 155—115)

1

This invention relates to a theatre chair and has for its primary object to facilitate the entrance and exit of persons through the aisles between the chairs.

Another object is to enable the occupant of the chair to move into the space between the arms thereof to permit the passage of a person along the row in front of the chair.

The above and other objects may be attained by employing this invention which embodies among its features a pair of side frames, a guide channel carried by each side frame, rollers mounted to move in the guide channels and a seat carried by the rollers and extending between the guide channels.

Other features include a back cushion carried by certain of the rollers and extending between the guide channels, said back cushion being pivotally coupled to the seat cushion whereby both cushions will move in unison longitudinally of the channels and means yieldingly to hold the back cushion in lowered position and the seat cushion in forward position between the channels.

Still other features include a hand lever pivotally supported on one of the side frames, means coupled to the hand lever and to the back cushion for moving the back cushion against the effort of the yielding means, and releasable means to lock the hand lever in elevated position to hold the seat retracted and the back cushion elevated against the effort of the yielding means.

Still other features include pivotally supporting the seat cushion supporting panel to permit it to swing upwardly toward the back cushion when the back cushion is lowered and the seat cushion is projected.

In the drawings:

Figure 1 is a top plan view of a theatre chair embodying the features of this invention.

Figure 2 is a side view of the chair illustrated in Figure 1.

Figure 3 is a front view of the chair illustrated in Figure 1, certain portions being broken away more clearly to illustrate certain details of construction.

Figure 4 is a longitudinal sectional view taken substantially along the line 4—4 of Figure 1.

Figure 5 is a horizontal sectional view taken substantially along the line 5—5 of Figure 2.

Figure 6 is a longitudinal sectional view taken substantially along the line 6—6 of Figure 1.

Figure 7 is a longitudinal sectional view taken substantially along the line 7—7 of Figure 1.

Figure 8 is a vertical sectional view taken substantially along the line 8—8 of Figure 4,

2

Figure 9 is a perspective view of the supporting panels for the seat and back cushions,

Figure 10 is a fragmentary rear view of the back cushion supporting panel, and

Figure 11 is a sectional view taken substantially along the line 11—11 of Figure 7.

Referring to the drawings in detail this improved theatre chair designated generally 10 comprises a base 12 to opposite side edges of which are attached side frames 14 and 16. A back panel 18 extends between the rear edges of the side frames 14 and 16, and fixed to adjacent faces of the frames 14 and 16 are guides designated generally 20. Each of these guides comprises a channel which is bent intermediate its ends to form a horizontally extending leg 22 and an upwardly and rearwardly inclined leg 24. In the preferred form of the invention the leg 22 is hingedly coupled to the lower forward end of the leg 24 as at 26, to permit the leg 22 to fold upwardly as suggested by the dotted lines in Figure 4. The guide channels 20 are attached to their respective side frames 14 and 16 so that the flanges of the channels project toward one another, and the bottom flange of the forward leg of each channel is bent upwardly as at 28 to form a stop for the rollers to be more fully hereinafter described. As shown the bottom legs 22 of the guide channels 20 are supported in spaced horizontal relation to the base or bed 12 of the chair, in order to hold the chair seat in proper spaced relation from the floor.

Mounted for longitudinal movement on the leg 24 of each guide channel 20 are rollers 30 which are rotatably mounted at opposite ends of transversely extending shafts 32 to which a back panel 34 is welded or otherwise rigidly secured. This back panel supports the back cushion 36 of the chair, and the rollers riding in the legs 24 of the guide channels 20 permit the back panel to move longitudinally of the leg 24 as suggested by the dotted lines in Figures 4 and 7. Hingedly coupled as at 38 to the lower end of the back panel 34 is a link 40 which curves downwardly and forwardly and has pivotally connected to its lower end as at 42 a link 42. These links 38 and 42 are each provided with a transversely extending shaft 44 upon opposite ends of which guide rollers 46 are mounted for reception in the curved portions of the guide channels 20 at the lower ends of the legs 24 when the seat is projected and the back is in lowered position. Hingedly coupled as at 48 to the lower forward end of the link 42 is a seat panel 50 which like the back panel 34 has fixed thereto 55 in spaced parallel relation on its underside a pair

of axle shafts 52 adjacent opposite ends of which are mounted for rotation guide rollers 54 which are adapted to be received in the horizontal legs 22 of the guide channels 20 when the seat is projected forwardly and the back is in its lowered position. In this position the chair is ready for occupancy. Suitable cushions 56 are fitted on the links 38 and 42, and a seat cushion 58 is attached to the seat panel 50 to cooperate with the back cushion 36 in forming a comfortable seat for the occupant.

As illustrated a chamber 60 is formed in the back of the chair immediately behind the back panel 34 and the rear panel 10, and fixed to the back panel 34 adjacent its lower edge and projecting into the chamber 60 is a horizontally extending bracket 62 carrying intermediate its ends a depending eye 64 to which the upper end of a retractile coil spring 66 is coupled. An eye 68 is coupled to the base or bed 12 directly below the eye 64, and the lower end of the coil spring 66 is anchored in the eye 68 so as yieldingly to hold the back panel and back cushion downwardly, and the seat cushion and seat panel projected as illustrated in the drawings. It will thus be seen that the back and seat panels will be yieldingly held in a position for comfortable seating of the occupant.

The side frame 14 of the chair 10 is provided in its top with an elongated longitudinal slot 70, and pivotally supported as at 72 within the side frame 14 is a hand lever 74, the free end of which projects through the slot 70 and is equipped with a push button 76 which is connected at its inner end to one end of a conventional Bowden wire 78, the opposite end of which is connected to a laterally extending latch dog 80 which operates through a slot 82 formed in one side of the hand lever 74, so that as the button 76 is pressed inwardly, the latch dog 80 will be moved toward the pivot 72 of the hand lever 74. A compression coil spring 84 is contained within the hand lever 74 between its pivot point and the underside of the latch dog, yieldingly to urge the latch dog outwardly with relation to the axis of the pivot 72. Fixed to the frame 14 adjacent the side of the hand lever 74 through which the latch dog 80 projects is a quadrant 86 which is equipped adjacent one end with a notch 88 for the reception of the latch dog 80 when the lever is in its elevated position. It will thus be seen that when the lever moves upwardly to its fullest extent, the latch dog 80 will engage in the notch 88 in the quadrant 86, and hold the lever elevated until such time as pressure is exerted on the push button 76 which operating through the Bowden wire 78 will release the latch dog from engagement in the notch 88 and permit the lever to return to its lowered position. A flexible cable 90 is coupled at one end to the lever 74 intermediate its ends, and this cable is trained over a guide pulley 92 arranged in the side frame 14 in front of the lever 74. Leading backwardly from the guide roller 92, the cable is trained over a guide roller 94 mounted in the side frame 14 adjacent the rear end thereof, so that the cable 90 will be directed into the chamber 60. Passing upwardly over a pair of spaced guide rollers 96 which are attached to the back panel 10 near its upper end, the end of the cable 90 remote from that which is connected to the hand lever 74 is extended through an opening in the bracket 62 near the spring 66, and is held in place by a conventional cable clamp 98, so that as the hand lever 74 is swung about the pivot 72 toward the back of the

chair 10, pull will be exerted on the cable 90 to cause the bracket 62 to be lifted against the effort of the spring 66, and thus move the back panel 34, intermediate panels 38 and 42, and the seat panel 50 longitudinally of the guide channels 20, so as to retract the seat and make room for the user to stand between the side frames 14 and 16. Obviously the frames 14 and 16 and the rear panel 10 may be covered in any suitable upholstering material to match or contrast with that used on the cushions 36, 56 and 58.

In use when a person desires to pass between a row of chairs, the occupants of the chairs may manipulate the hand levers 74 by moving them upwardly about the axes of the pivots 72, thus exerting pull on the cables 90 and moving the seat cushions 58 rearwardly so that they may stand between the side panels 14 and 16 of their respective chairs 10. Upon reaching its fullest extent of movement, the lever will move the dog 80 into alinement with the notch 88 so that the dog will engage in the notch and hold the seat retracted, thus relieving the occupant of the chair of any strain while persons are passing in front of him. As soon as the aisle has cleared, pressure may be exerted on the push button 76, thus to move the dog 80 out of the notch 88 and thus permit the lever to swing about its pivot 72 and allow the seat and back cushions to move under the influence of the spring 66 and assume their previous positions. The seat cushion and front panel may be lifted as suggested by the dotted lines in Figure 4, thus swinging the arms 22 of the guide channels 20 about the pivots 26 so as to give access to the space beneath the seat cushion from the top thereof.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a theatre chair a pair of spaced parallel side frames, a guide channel carried by each side frame, each guide channel having a horizontal seat supporting leg and an upwardly and rearwardly extending back supporting leg, rollers movable longitudinally in the guide channels, a seat cushion carried by certain of the rollers and extending between the horizontal legs of the guide channels and a back cushion carried by other rollers and extending between the upwardly and rearwardly inclined legs of the guide channels and the seat cushion and back cushion being pivotally coupled to one another for movement in unison longitudinally of the channels, a spring coupled to the back cushion yieldingly to hold it in its lowermost position, a hand lever mounted in one of the side frames for movement in a vertical arc and means coupling the hand lever with the back cushion for moving said back cushion upwardly against the effort of the spring.

2. In a theatre chair a pair of spaced parallel side frames, a guide channel carried by each side frame, each guide channel having a horizontal seat supporting leg and an upwardly and rearwardly extending back supporting leg, rollers movable longitudinally in the guide channels, a seat cushion carried by certain of the rollers and extending between the horizontal legs of the guide channels and a back cushion carried by other rollers and extending between the upward-

ly and rearwardly inclined legs of the guide channels and the seat cushion and back cushion being pivotally coupled to one another for movement in unison longitudinally of the channels, a spring coupled to the back cushion yieldingly to hold it in its lowermost position, a hand lever mounted in one of the side frames for movement in a vertical arc and a flexible member coupled at one end to the back cushion and at its opposite end to the hand lever to cause the cushion to move against the effort of the spring when the hand lever is moved toward the back of the side frame.

3. In a theatre chair, in combination, a pair of spaced parallel side frames, a guide channel carried by each of said side frames, each of said guide channels comprising a substantially straight horizontal portion, a substantially straight upwardly and rearwardly extending inclined portion, and a curved portion tangentially joined to both of said straight portions, a seat board, a back board, at least one intermediate board hingedly connected to said seat and back boards, first rollers secured to said seat board and movably disposed in said horizontal channel portions, second rollers secured to said back board and movably disposed in said inclined channel portions, and third rollers secured to said intermediate board and movably disposed in said curved channel portions, the spacing between the outermost ones of said rollers in the direction of said channels being less than the effective length of each of said channels, thereby permitting movement of all of said boards in unison and in the direction of the respective channel portions.

4. In a theatre chair, in combination, a pair of spaced parallel side frames, a guide channel carried by each of said side frames, each of said guide channels comprising a substantially straight horizontal portion, a substantially straight upwardly and rearwardly extending inclined portion, and a curved portion tangentially joined to both of said straight portions, abutment means at each end of each guide channel, an upholstered seat board, an upholstered back board, a plurality of upholstered intermediate boards hingedly connected to one another and to said seat and back boards, two spaced

pairs of first rollers secured to said seat board and movably disposed in said horizontal channel portions, two spaced pairs of second rollers secured to said back board and movably disposed in said inclined channel portions, and a plurality of pairs of third rollers each secured to a respective one of said intermediate boards and movably disposed in said curved channel portions, the distance between the foremost of said pairs of first rollers and the uppermost of said pairs of second rollers, measured along said guide channels, being less than the length of each of said channels between the said abutment means thereof, thereby permitting limited movement of all of said boards in unison and in the direction of the respective channel portions.

5. In a theatre chair a pair of spaced parallel side frames, a guide channel carried by each side frame, each guide channel having a horizontal seat supporting leg and an upwardly and rearwardly extending back supporting leg, rollers movable longitudinally in the guide channels, a seat cushion carried by certain of the rollers and extending between the horizontal legs of the guide channels and a back cushion carried by other rollers and extending between the upwardly and rearwardly inclined legs of the guide channel, the seat cushion and back cushion being pivotally coupled to one another for movement in unison longitudinally of the channels, and means for selectively moving said back cushion into an upward or downward position.

GROVER CLEVELAND JONES.
